CONTROL CABINET FOR ELECTRICAL APPARATUS

Guy D. Bradley and James R. Chapin, Erie, Pa., assignors
to General Electric Company, a corporation of New
York

Filed July 12, 1965, Ser. No. 86,124

Term of patent 14 years

(Cl. D26—1)

FIG. 1

FIG. 2

FIGURE 1 is a front perspective view of a control cabinet for electrical apparatus showing our new design; and

FIGURE 2 is a rear perspective view thereof.

The side not shown is substantially a mirror image of the side shown.

We claim:

The ornamental design for a control cabinet for electrical apparatus, as shown and described.
